UNITED STATES PATENT OFFICE.

JACOB I. ROBIN, OF NEW YORK, N. Y.

DESIGN FOR A CASING FOR A LOUD SPEAKER.

Application filed March 29, 1927. Serial No. 21,395. Term of patent 7 years.

To all whom it may concern:

Be it known that I, JACOB I. ROBIN, residing at New York, in the county of and State of New York, have invented a new, original, and ornamental Design for a Casing for a Loud Speaker, of which the following is a specification, reference being had to the accompanying drawing, forming part thereof.

Fig. 1 is a front view of the casing for a loud speaker showing my new design, Fig. 2 is a side view thereof, and Fig. 3 a rear view thereof.

I claim:

The ornamental design for a casing for a loud speaker, as shown.

JACOB I. ROBIN.
